UNITED STATES PATENT OFFICE.

OSCAR L. COFFEY, OF HARVEY, ILLINOIS, ASSIGNOR TO WHITING CORPORATION, OF HARVEY, ILLINOIS, A CORPORATION OF ILLINOIS.

DROP-PIT MECHANISM FOR UNWHEELING LOCOMOTIVES.

Application filed January 10, 1925. Serial No. 1,518.

REISSUED

To all whom it may concern:

Be it known that I, OSCAR L. COFFEY, a citizen of the United States, residing at Harvey, in the county of Cook and State of Illinois, have invented a certain new and useful Improvement in Drop-Pit Mechanism for Unwheeling Locomotives, of which the following is a specification.

This invention relates to so-called drop pits for removing heavy wheels from vehicles of various kinds, specifically: railroad locomotives. The principal object of the invention is to provide a pit construction and wheel carrying mechanism operating therein adapted to transport a pair of wheels from a vehicle, such as a locomotive, to a point on another track in such a position and condition that they may be rolled away for work to be done upon them.

The invention consists in mechanism capable of attaining the foregoing and other objects; which can be comparatively easily and cheaply made; which is satisfactory in use and is not readily liable to get out of order, and particularly in such a device which is operative to selectively transport wheels from separate locomotives on a multiplicity of separated tracks to a common point of delivery of the wheels for work thereon.

More particularly the invention consists in numerous features and details of construction which will be hereafter more fully described in the specification and claims.

Referring to the drawings in which like numerals designate like parts throughout the several views:

Figure 1 is a plan view of mechanism illustrating this invention in its preferred form.

Figure 2 is a side elevation taken on the irregular line 2—2 of Figure 1.

Figure 3 is an end elevation taken on the irregular line 3—3 of Figure 1.

Figure 4 is a reduced size, changed position view of the parts of Figure 3, taken from the extreme right hand end of Figure 1.

Figure 5 is a plan view of the complete pit, equipped with the mechanism of this invention, showing the same applied in curved form as would be required if applied in or in proximity to a round house.

Figure 6 is a side elevation, taken on the line 6—6 of Figure 5.

The mechanism of this invention is ap-

plicable to a multiplicity of adjacent but spaced railroad tracks 10—12 and 14 crossing the top of an intersecting pit 16, preferably but not necessarily entirely open at its top, there being in the bottom of the pit a track 18 along which the wheel transporting trolley 20 travels across the lines of tracks 10—14. This trolley 20 is, in the particular case here illustrated, made up of side frames 22 and cross beams 24, rigidly connected thereto, the side frames including blocks 26 located over the rails 18 and adapted when the load on the trolley exceeds a certain point to, through the spring construction 28, interposed between the trolley and its supporting wheels 30, rest upon the track rails 18 and thus take the strain off the wheels, all as more fully described and claimed in companion application, Serial Number 1517, filed herewith. The trolley as a whole is propellable along the rails 18 by any suitable means, in the particular case here illustrated by the rocking of hand manipulatable levers 32, equipped with ratchet dogs 34 selectively engageable with the teeth 36 on ratchet wheel 38, on the shaft 40 of the adjacent wheels 30, all as more fully described and shown in said companion application.

Rising from and rigidly attached to four corners of the trolley 20 are four load carrying screws 42, each having threaded thereon a worm wheel 44 meshing with a suitable worm 46 enclosed in an oil or grease retaining case 48. The worms 46 are connected together in pairs by shafts 49, each carrying a bevel pinion 50 meshing with another bevel pinion 52. These two last mentioned pinions are on a common shaft 54 carrying a gear 56 driven by a pinion 58 on the shaft of an electric motor 60 or other suitable source of power receiving its energy from a source not shown outside the machine. Each two cases 48 over a given track rail 18 are rigidly connected to box girders 62 made up, as clearly shown in Figures 3 and 4, of spaced channel irons. Each two cases 48 which are opposite each other transversely of the track are connected together by cross beams 64 rigidly secured in position by any suitable means, as, for instance, the angles 66, suitably secured to these cross beams and the adjacent channels of the box girders 62. The box girders 62 are equipped with spreaders 68, carried by bolts 70 which insure the side channel irons of the girders

being almost the same distance apart and consequently capable of separably interfitting, as shown in Figure 3, with depending members—in the particular case here illustrated, longitudinally disposed girders 72, extending parallel with rails 18 and forming a part of wheel sustaining table 74, equipped with rail sections 76, selectively interfittable with at least one of the tracks 10 as 10 or 14 which carry the locomotives and the track, as 12, on which the removed wheels are finally disposed of.

The wheel table 74 is equipped with reciprocal latch bars 78 manipulatable through the agency of connecting rods 80, toggles 82 and hand lever 84, from the position shown in Figure 3 where the ends of the latches enter slots 86 in the side walls of the pit 16, and rest upon stationary supports 88 20 to a retracted position in which they are drawn inward sufficiently to clear these supports and thus permit the wheel table to rest upon and travel with the upper frame 62—64 as more fully appears hereafter. 25 From the foregoing, it clearly appears that the wheel table 74 can be locked in position in the tracks 10—12 or 14 and that when so positioned, the frame 62—64 can be lowered and the trolley 20 can then be run 30 along track 18 (as shown in Figure 4) without in any way interfering with such locked in position wheel table 74.

Upwardly projecting guides 90 having faces 92 and 94 angularly inclined in planes 35 at approximately right angles to each other insure the accurate interfitting of the lifting mechanism and the wheel carrying table 74 when the operator causes the lifting mechanism to move from the position of 40 Figure 4 upward to the position of Figure 3.

Attention is called to the fact (clearly shown in Figure 4) that the tops of the screws 42 amply clear the projecting members, specifically the girders 72 on the lower side of wheel tables 74, the significance being that as many tracks 10—14 as desired, intersected by the pit 16, may be provided, all of said tracks except one being equipped with a wheel table 74 and that the trolley 20 may then go to any track having a table 74, connect up with that table as shown in Fig. 3, have the latches 78 released, and then lower the table 74 to a point below the tops of the screws 42 and thereupon carry 55 said table under the tables of any other intervening tracks to the opening in the track which did not initially have a wheel table, and by raising the carrying wheel table, place it in that track. This is of importance in that the mechanism is capable of serving a multiplicity of tracks to deliver wheels from locomotives on those tracks to a common track, as 12, for work upon those wheels, this while leaving all of the tracks, except the service track 12, complete so that

locomotives or other machines to be de-wheeled can move at will over the different tracks, regardless of the position of the trolley 20 along the rails 18 in pit 16. This lowering of the table 74 to the position in Figure 4 is rendered possible, as clearly shown, in Figure 1, by omitting all obstructions in alignment with the screws 42 from the table structure 74.

In the operation of the entire mechanism, 75 assume that the parts are in initial position of all the figures, except Figure 4, and that a locomotive 96 is standing with its wheels 98 on rail sections 76 of the table 74, installed for the time being, if not regularly 80 belonging in track 10. The operator now starts motor 60 to ultimately rotate worm wheels 44 in unison to slightly raise lifting frame 62—64 and consequently wheel table 74 and wheels 98 to a point at which latches 78 can be freely withdrawn by the operator's 85 easily manipulating lever 84. If this upward movement has applied too much of the weight of the entire locomotive to the lifting mechanism, springs 28 compress and blocks or shoes 22 settle upon the rails 18, thus taking the load off wheels 30 as described and claimed in the companion application, heretofore mentioned. When this extreme upward position is reached, the motor 60 is stopped and the operator blocks up or otherwise secures the springs, not shown, on the locomotives and detaches the wheels 98 which now rest only upon rail section 76 of table 74. The operator now 95 starts the motor 60 in the opposite direction, thus causing the entire mechanism shown at the top of Figure 1 and between the guides 100 on opposite pit walls to descend to such point along screws 42, say the position of Figure 4 or lower, wherein the lifting mechanism and the wheels 98 thereon 100 entirely clear the wheel table 74 in any other track 1—14 under which the wheel is to be carried. The moment the wheels 98 descend 110 to a point where they only are carried by the table 74, the springs 28 return the blocks 22 to the normal position of Figure 2 in which they slightly clear the rails 18. When the wheels have been lowered sufficiently, the operators manipulate one or both of the levers 32 to propel the trolley 20 and everything on it along the pit until the table 74, which has just been removed from track 115 10 is in proper position with reference to the service track, say track 12, on which the wheels are to be taken away. The operator having stopped motor 60 before manipulating levers 32 now starts the motor 120 to cause upward movement of the table 74. This movement is continued until the latches 78 are in position to slip over the supports 88 belonging to that particular track, as 12, whereupon the lever 84 is manipulated to 125 throw those latches into extended position.

The motor 60 is now operated to lower the lifting mechanism until these latches actually rest upon supports 88 of the particular track, as 12, in which the table 74 has been placed. In this condition of affairs, the wheels 98 may be rolled off upon the adjacent track, as 12. The table 74, which has thus been brought and placed in track 12, may now be returned to original position 10 in track 10 by reversing the operations described or this table may be left indefinitely in track 12 and the machine manipulated in obvious manner until the parts assume the position of Figure 4 whereupon the trolley 15 20 can be moved along the track 18 to another track, as 14, whose table 74, with or without wheels thereon, is to be transported into any track 10—14 which has no table 74 in it, under the conditions just described, 20 track 10.

The drawings show a completely open pit 16 but there is nothing in the structure of the invention which requires any surface opening between the tables 74 in elevated 25 position or the respective adjacent tracks. In other words, if the pit is made deep enough and the screws 42 are made of corresponding length, the table 74 and wheels thereon may be carried down to a sufficient 30 depth in the pit 16 to carry the wheels under any desired roof construction placed over the top of the pit. In this aspect, the invention is usable in transporting a track table between two adjoining pit top openings 35 in the same track as well as under the conditions shown, wherein the effective openings are in parallel tracks.

In the specific embodiment of the invention, the pit 16 is curved from the center of 40 intersection below Figure 5 of tracks 10—14. Obviously, if the tracks were parallel to each other, the pit 16 would be straight and at right angles thereto.

Having thus described my invention, 45 what I claim as new and desire to secure by Letters Patent is:

1. In mechanism of the class described, in combination with means passing a wheeled vehicle over the ground, and a pit below it, having a multiplicity of separated wheel tables each equipped with means detachably latching it across said pit, a track in the bottom of the pit passing under said tables, a trolley travelable along said track, table elevating means on and reciprocal vertically above the trolley, movable between a position where it engages and lifts a table which it may be under, high enough so its latching mechanism may be released, and a position low enough so that the trolley with said table and a wheel load thereon may move along said track under one or more other such wheel tables.
2. In mechanism of the class described, in combination with means passing a wheeled

vehicle over the ground, and a pit below it, having a multiplicity of separated wheel tables each equipped with means detachably latching it across said pit, a track in the bottom of the pit passing under said tables, 70 a trolley travelable along said track, table elevating means on and reciprocal vertically above the trolley, movable between a position where it engages and lifts a table which it may be under, high enough so its latching mechanism may be released, and a position low enough so that the trolley with said table and a wheel load thereon may move along said track under one or more other such wheel tables, and power 80 means manipulating the table elevating means.

3. In mechanism of the class described, in combination with means passing a wheeled vehicle over the ground, and a pit below it, having a multiplicity of separated wheel tables each equipped with means detachably latching it across said pit, a track in the bottom of the pit passing under said tables, 85 a trolley travelable along said track, table elevating means on and reciprocal vertically above the trolley, movable between a position where it engages and lifts a table which it may be under, high enough so its latching mechanism may be released, and a position low enough so that the trolley with said table and a wheel load thereon may move along said track under one or more other such wheel tables, and power 90 means manipulating the table elevating means.

4. In mechanism of the class described, in combination with means passing a wheeled vehicle over the ground, and a pit below it, having a multiplicity of separated wheel tables each equipped with means detachably latching it across said pit, a track in the bottom of the pit passing under said tables, a trolley travelable along said track, 100 table elevating means on and reciprocal vertically above the trolley, movable between a position where it engages and lifts a table which it may be under, high enough so its latching mechanism may be released, and a position low enough so that the trolley with said table and a wheel load thereon may move along said track under one or more other such wheel tables, said power 105 means including a multiplicity of stationary screws rising from the trolley.

5. In mechanism of the class described, in combination with means passing a wheeled vehicle over the ground, and a pit below it, having a multiplicity of separated wheel tables each equipped with means detachably latching it across said pit, a track in the bottom of the pit passing under said tables, 110 a trolley travelable along said track, table elevating means on and reciprocal vertically above the trolley, movable between a position where it engages and lifts a table which it may be under, high enough so its latching mechanism may be released, 115 and a position low enough so that the trolley with said table and a wheel load thereon may move along said track under one or more other such wheel tables, and power means manipulating the table elevating 120 means, said power means including a multiplicity of stationary screws rising from the trolley.

elevating means on and reciprocal vertically above the trolley, movable between a position where it engages and lifts a table which it may be under, high enough so its latching mechanism may be released, and a position low enough so that the trolley with said table and a wheel load thereon may move along said track under one or more other such wheel tables, said power means including a multiplicity of stationary screws rising from the trolley, a frame carrying worm wheels traversing in unison said screws and a motor.

6. In mechanism of the class described, in combination with means passing a wheeled vehicle over the ground, and a pit below it, having a multiplicity of separated wheel tables each equipped with means detachably latching it across said pit, a track in the bottom of the pit passing under said tables, a trolley travelable along said track, table elevating means on and reciprocal vertically above the trolley, movable between a position where it engages and lifts a table which it may be under, high enough so its latching mechanism may be released, and a position low enough so that the trolley with said table and a wheel load thereon may move along said track under one or more

other such wheel tables, power means 30 manipulating the table elevating means, said power means including a multiplicity of stationary screws rising from the trolley, a frame carrying worm wheels traversing in unison said screws and a motor. 35

7. In mechanism of the class described, in combination with means passing a wheeled vehicle over the ground, and a pit below it, having a multiplicity of separated wheel tables each equipped with means detachably 40 latching it across said pit, a track in the bottom of the pit passing under said tables, a trolley travelable along said track, table elevating means on and reciprocal vertically 45 above the trolley, movable between a position where it engages and lifts a table which it may be under, high enough so its latching mechanism may be released, and a position low enough so that the trolley with said table and a wheel load thereon may move along said track under one or more other such wheel tables, and angular guides insuring proper interfitting of the table elevating means and adjacent wheel table. 50

In witness whereof, I have hereunto subscribed my name.

OSCAR L. COFFEY.
